UNITED STATES PATENT OFFICE.

PETER D. BENWAY, JR., OF SOUTHBRIDGE, MASSACHUSETTS.

NECKTIE-FASTENER.

SPECIFICATION forming part of Letters Patent No. 358,721, dated March 1, 1887.

Application filed November 20, 1886. Serial No. 219,486. (No model.)

To all whom it may concern:

Be it known that I, PETER D. BENWAY, Jr., of Southbridge, in the county of Worcester and State of Massachusetts, have invented certain new and useful Improvements in Necktie-Fasteners; and I do hereby declare that the following is a full, clear, and exact description of the invention, which will enable others skilled in the art to which it appertains to make and use the same, reference being had to the accompanying drawings, which form a part of this specification, and in which—

Figure 1 is a view of the back of a scarf provided with my improved fastener. Fig. 2 is a view of the fastener in operative position, and Fig. 3 is a view of the fastener folded out to show its component parts.

Similar numerals of reference indicate corresponding parts in all the figures.

20 My invention has relation to fasteners for that class of scarfs having a pasteboard shield or shield of other similar stiff material at its back; and it consists in the improved construction and combination of parts of such a fastener, which may be hooked to the said shield, and which is provided with a loop or eye, which may be secured upon the collar-button for the purpose of securing the scarf; and it consists in the improved construction 25 and combination of parts of such a fastener, as hereinafter more fully described and claimed.

In the accompanying drawings, the numeral 1 indicates the shield of the scarf, which shield may be formed of any suitable stiff material, 30 and may be of any size and shape, and to which the fastener is secured.

The fastener is made from spring-wire, and is formed into an oblong loop or eye, 2, having preferably its upper doubled end, 3, narrower 40 than the central portion, and the arms of this loop are crossed and bent straight outward in opposite directions, as shown at 4. The outer ends of these straight portions are formed into flat coils 5, and the ends 6 of these coils 45 are bent obliquely upward, crossing each other and formed with eyes 7 at their ends, the said crossing arms being preferably bent slightly inward in a plane parallel to the plane of the inner ends, the bends being shown at 8. The 50 eyed ends 9 of the diverging arms 10 of a doubled hook, 11, are secured into the eyes of the crossing arms of the main portion, and the

hook is bent inward and upward, pending downward from the eyed ends of the crossing arms at the inner side of the main portion of 55 the fastener. A narrow bail, 12, has its doubled end bent or curved so as to form eyes 13 at the ends of the end bar of the bail, and the ends of the arms of the bail are bent to form hooks 14, projecting inward and downward, the hooked ends of the bail being above the doubled end, which is secured with the eyes upon the diverging straight arms of the main portion.

The fastener is secured to the shield of the 65 scarf by hooking the hooked ends of the bail into the upper edge of the shield, placing the arms of the bail under the sides of the loop, and the diverging arms of the main portion are drawn downward by means of the doubled 70 hook until the said hook may be hooked under the lower edge of the shield, when it will be seen that the elasticity of the coils in the main portion of the fastener will draw the hooks together and clamp the shield edgewise, securing the fastener firmly to the shield, when the loop may be buttoned upon the collar-button, securing the scarf to the same in its proper position.

It will be seen that this device will be very 80 useful with scarfs in which either the elastic loop upon the shield for attachment upon the collar-button or the straps for securing it around the neck have been removed or lost, enabling the scarf to be used while the front 85 portion and the shield is in good condition, regardless of the condition of the fastenings for the scarf; and it will also be understood that the device may be applied to new scarfs as an original fastener.

Having thus described my invention, I claim 90 and desire to secure by Letters Patent of the United States—

1. A scarf-fastener consisting of a main portion having a loop, 2, formed with a narrow 95 upper doubled end, and having its ends crossed and bent to form diverging straight portions having coils 5, then bent to cross each other again and formed with an eye, 7, at each end, a doubled hook, 11, having diverging arms 100 formed with eyes 9 at their upper ends, secured in the eyes of the main portion, and a narrow bail, 12, having its lower doubled end bent to form eyes 13 at the ends of the end bar, se-

cured upon the straight diverging arms of the main portion, and having its upper ends bent to form inwardly and downwardly projecting hooks 14, as and for the purpose shown and set forth.

2. In combination with a scarf having a stiff shield at its back, a fastener composed of a main portion having an upwardly-projecting narrowing loop, 2, having its ends crossed and formed with straight diverging portions having flat coils 5, and straight end portions crossed again and provided with an eye, 7, at each end, a doubled hook, 11, having the eyed ends 9 of its diverging arms secured in the 15 eyes of the main portion, and having the

doubled hook engaged under the lower edge of the shield, and a narrow bail, 12, having its doubled end bent to form eyes 13 at the ends of its end bar, secured upon the straight diverging arms of the loop, and having hooks 14 20 at its upper ends engaging the upper edge of the shield, as and for the purpose shown and set forth.

In testimony that I claim the foregoing as my own I have hereunto affixed my signature in 25 presence of two witnesses.

PETER D. BENWAY, JR.
